IGNITION SYSTEM.

1,254,182.

Specification of Letters Patent. Patented Jan. 22, 1918.

Application filed May 29, 1917. Serial No. 171,609.

To all whom it may concern:

Be it known that I, LEO J. WERNER, a citizen of Russia, residing at Newark, in the county of Essex and State of New Jersey, have invented certain new and useful Improvements in Ignition Systems, of which the following is a specification.

In starting internal combustion engines where the engine is large or the grade of fuel low it is very essential that ignition 10 sparks be obtained at low rotative speeds of the engine. After the engine has been started it has been found that the magneto will enable the engine to give the fullest 15 amount of power which it is capable of delivering and it has, therefore, been the practice, in a great many cases, to use an auxiliary source of ignition for starting, such as a battery and coil or a specially arranged 20 starting magneto. Many engines are started "on compression" due to the fact that an internal combustion engine will stop with a charge of combustible gas, in a partially 25 compressed state, in one or more of the cylinders, depending on the number thereof, so that if a spark is produced in this cylinder it will usually start the engine. In aero- 30 plane work where the engine cannot be started "on compression" after having been out of use for some time it is customary to take hold of the propeller blades and turn 35 the engine over, to draw gas into the engine cylinders, and then to switch on the ignition and operate the starting magneto, or its equivalent, which in many cases has no mechanical connection with the service magneto or any of the driving parts of the engine.

It is an object of my invention to over- 40 come the difficulty of hard starting by providing means of obtaining a spark or shower of sparks, at the proper time, no matter how slow the rotative speed of the engine is, while I also provide means for utilizing the 45 magneto for service ignition.

It is another object of my invention to provide a system that will be applicable to aero and hydro plane engines as well as to automobile and marine engines.

50 In starting the engine it is essential that the spark be retarded so that no back-kick will result and it is another object of my invention to arrange and coördinate the parts entering into my system in such man-

ner that when starting on the auxiliary 55 source of ignition current it will be practically impossible to get a back-kick, even though the spark timing lever be left considerably advanced, all of which will be apparent after a study of the specification and 60 drawing.

Further objects of my invention will be apparent to one skilled in the art without specifically pointing them out.

Figure 1 is a diagrammatic view of the 65 parts entering into my ignition system, showing the service magneto and its circuit breaker and distributor together with the auxiliary source of starting current and controlling switch for both sources of ignition 70 current.

Fig. 2 is a detail illustrating the method of insulating the auxiliary stationary contact on the main breaker box.

In the drawing, 1 illustrates a service 75 magneto used for furnishing ignition current to the engine under normal running. The magneto shown is of the "Dixie" inductor type, having field pole pieces 2 and 3 between which are rotated inductors 4 and 5 80 by means of shaft 6. Bridging the pole pieces 2 and 3 is a yoke 7 on which is wound the primary 8 of an induction coil, and secondary 9. The breaker box 10, which is shown diagrammatically below the magneto 85 1, is adapted to be carried thereon in any suitable manner. Pivotedly mounted on the breaker box is the usual breaker arm 11 carrying a contact 12. Stationary contact 13, properly insulated from the breaker box, 90 carries an adjustable contact 14. Breaker arm 11 carries a piece of wearing material 15, usually fiber, which is adapted to be engaged by the cam 16 carried on the shaft 6. Mounted on the breaker box 10, and insulated therefrom by suitable insulators shown 95 in Fig. 2, is a stud 17 carrying an adjustable contact 18 which coöperates with the contact 19 carried on the member 20, that is fastened to the end of the breaker arm by a bolt 21 100 which passes through the wearing piece 15, thereby serving to hold the member 20 and wearing piece 15 to the breaker arm 11, which is connected to the metal frame work of the breaker box through its mounting 105 thereby grounding the same to the frame work of the magneto. The magneto 1 carries a distributor block 22 which is shown on

a more enlarged scale at the upper part of the drawing. Within the distributor block 22 is a distributor finger 23 in the end of which is an annular metal ring 24. Running on the metal ring 24 is a brush 25 connected to terminal post 26 on the block 22. The finger 23 carries a brush 27 which distributes current, received through brush 25 running on the ring 24, to a suitable number 5 of distributing contacts 28, only one of which is illustrated. Finger 23 is driven by a gear 29 that is adapted to be operated by pinion (not shown) which may be attached to shaft 6. Fastened to the distributor block 10 15 22 is a spindle 30 which passes through the insulator 31. The spindle 30 serves to connect the end of the secondary winding 9 to the binding post 32. The switch 33 carries on a suitable insulating block a series of 20 studs 34 to 45 inclusive. A switch lever 46 is adapted to operate a movable blade on which is suitably mounted three metallic sectors 47, 48 and 49. The sector 47 is of suitable size to bridge three contact studs 25 while the sector 48 is of suitable size to bridge two and the sector 49 is of suitable length to bridge either the studs 43 and 44 or 44 and 45, for the purpose to be pointed out later.

30 I is an induction coil having a vibratory arm 53 connected to the primary 50, one end of which is grounded. 52 illustrates the magnetic core of the induction coil I and 51 is the secondary, one end of which is grounded, the other end of which is connected to contact stud 45. The contact stud 43 is connected to terminal post 32 of the distributor block 22 and contact 44 is connected to terminal post 26. B is a suitable battery, one 35 terminal of which is connected to contact 54, preferably adjustable, of the induction coil I, the other terminal being connected to switch contact stud 34. Switch contact stud 35 is connected to stud 17 on the breaker box 10 while contact studs 37, 39 and 41 are interconnected and joined to the contact block 13 on the breaker box. One end of primary winding 8 is also connected to block 13. Contact studs 40 and 42 are interconnected and 45 joined to a stationary contact 55 upon which a switch lever 56 is adapted to impinge, the push switch lever 56 being connected to switch contact 36 and the latter cross connected to switch contact 38.

50 As shown in the drawing the switch 33 is illustrated with handle 46 in the battery position and in this position the circuit through the primary of the induction coil I, may be traced as follows: from ground, 55 winding 50 to contacts 53, 54, battery B to contact 34, through segment 47, contact 35 to stud 17 on the breaker box, through contacts 18 and 19, member 20, breaker arm 11 to ground. The secondary 51 is closed through the distributor by way of contact

45, segment 49, contact 44, terminal 26 to the brush 25 whence it is distributed by brush 27 to the various contacts 28 to the spark plugs of the engine cylinders.

In timing a magneto on an engine it is 70 customary practice to time the same so that the magneto breaker points, such as 12 and 14 are just beginning to separate when one of the pistons (considered as #1) reaches its maximum on the compression stroke with 75 the breaker box in its fully retard position. By referring to the breaker box illustrated in the drawing, it will be seen that under this condition the points 18 and 19 which are in the primary of the induction coil circuit will not be closed as it will be understood that they are only closed after the breaker points 12 and 14 have opened a considerable distance, relatively speaking. That is to say, the contacts 18 and 19 are 80 timed with respect to the engine considerably later than the contacts 12 and 14. As to the timing of the auxiliary or battery circuit, this is similar to the idea expressed in Lang application, Serial No. 68,688, filed 90 December 27, 1915, but the circuit controlling features of the battery system are much simpler than in the above mentioned Lang structure.

With the circuits in the condition described it will be seen that the induction coil I, produces ignition current to the spark plugs. At the same time it will be understood that the primary 8 of the service magneto 1 is grounded at 55 through contacts 39 100 and 40 by means of segment 48 so that the engine will run on the auxiliary or starting source of current until the switch handle 46 is thrown to magneto position, in which position it will be noted that the segment 105 49 connects contacts 43 and 44 together bringing into the distributor circuit the secondary winding 9 of the magneto, while the segment 47 is moved to cross the contacts 37 and 38 and the segment 48 is moved to a 110 neutral position shown in dotted lines at 57. In this position of the switch it will be possible, through the cross connections indicated, to ground the magneto by the push button 56 without throwing the switch 115 thereby stopping the engine. The switch 56 may also be used to start on compression with the switch in battery position, should at any time the contacts 18 and 19 be open at the circuit breaker. With the switch 120 lever 46 in the "off" position the segment 47 takes a neutral position, shown in dotted lines at 58, and the segment 48 takes the position to cross contacts 41 and 42 thereby grounding the magneto and thus stopping 125 the engine so that in addition to stopping the engine by means of the push lever 56 above described the engine may be stopped by throwing the switch to the "off" position.

By my arrangement of apparatus as above 130

described it will be seen that I have provided an auxiliary source of ignition current utilizing a main distributer, which in some cases may be mounted on the engine itself, and not on the service magneto and in which the same breaker arm that controls the service magneto also controls the action of the auxiliary ignition. While I have shown a high tension magneto of the "Dixie" type it will be understood that any other type of high tension magneto may be used and that various modifications may be made in the distributer, circuit breaker and switch since those shown are diagrammatic merely for illustrating the nature of my invention.

Having thus described my invention what I claim is:—

1. In an ignition system, the combination of a service magneto having primary and secondary windings, a circuit breaker carrying contacts on either end, one of which controls the circuit of said primary winding, an auxiliary ignition device having primary and secondary windings, an interrupter in circuit with said primary winding, a distributer, a switch for switching the secondary of the service magneto out of circuit and the secondary of the auxiliary ignition device into the distributer circuit, said switch also serving to connect the second contact of the said circuit breaker into circuit with the primary of the auxiliary ignition device, for the purpose described.

2. In an ignition system, the combination of a magneto for furnishing service sparking current, a circuit breaker for controlling the time of delivery of the sparking current of the magneto, a distributer for distributing sparking current to the spark plugs, an auxiliary ignition device for furnishing starting sparking current and a vibratory interrupter for causing a shower of sparks from said ignition device, a switch for switching the service sparking current out of the distributer and switching in the starting sparking current, said circuit breaker serving to time the delivery of sparks from the auxiliary ignition device at a later period than it times the current from the service magneto.

3. In an ignition system, the combination of a service magneto adapted to be positively driven and having a distributer for distributing sparking current to spark plugs, and a circuit breaker for timing the passage of the sparking current to said plugs, of a self operating ignition device and a source of current connected thereto, and a switch for directing the current from said ignition device into said distributer circuit at the same time completing a circuit through the source of power to a stationary contact adapted to coöperate with said circuit breaker for the purpose of timing the passage of sparking current to said

plugs at a period later than that of the service magneto.

4. In an ignition system, the combination of a service magneto having primary and secondary windings, a main circuit breaker carrying two contacts one of which is included in the circuit of said primary winding, a distributer, an induction coil having primary and secondary windings, a source of direct current, a stationary contact adapted to coöperate with the second of said contacts on the main circuit breaker, a switch for connecting the primary of said induction coil and battery in circuit with the last mentioned pair of contacts operated by the main circuit breaker, said switch also serving to connect the secondary of the induction coil with the distributer, as described.

5. In an ignition system, the combination of a service ignition device having primary and secondary circuits, a main circuit breaker controlling one pair of contacts included in the primary circuit, a distributer, an auxiliary ignition device having primary and secondary circuits, a source of current, a second pair of contacts brought into closed position by the main circuit breaker after the first pair has been moved to open position, and a switch for including the source of current in circuit with the primary of the auxiliary ignition device and the second pair of contacts and also connecting the secondary of the auxiliary ignition device into the distributer, as described.

6. In an ignition system, the combination of a source of service sparking current, a circuit breaker for controlling the time of delivery of the sparking current therefrom, a distributer for distributing the sparking current to spark plugs, an auxiliary source of sparking current and power means for operating the same, a switch for switching into the distributer the sparking current from the said auxiliary source in place of the sparking current from the service source, said switch also serving to switch an element of the said circuit breaker into a circuit whereby it controls the time of delivery of the sparking current from the auxiliary source so as to make it come at a period later than the current from the service source.

7. In an ignition system, the combination of a magneto for furnishing service sparking current, a circuit breaker for controlling the time of delivery of the sparking current therefrom, a distributer for distributing the sparking current to spark plugs, an auxiliary source of sparking current consisting of an induction coil having primary and secondary windings with a vibrator and battery in the primary circuit, a switch for switching into the distributer the sparking current from the said auxiliary source in

- place of the sparking current from the service magneto, said switch also serving to switch an element of said circuit breaker into circuit with the battery and vibrator whereby it controls the time of delivery of the sparking current from the auxiliary source so as to make it come at a period later than the current from the service source, said switch in this position serving also to disable the magneto.
8. In an ignition system, the combination with means for producing service sparking current adapted to be positively driven and a distributer for distributing the sparking current to spark plugs, and a circuit breaker having a pair of contacts for timing the passage of the sparking current to the spark plugs, of starting means operated by a battery and having an interrupter for producing sparking current impulses, a second pair of contacts controlled by said circuit breaker, at a later rotative period than the first, and a switch for directing the current from the starting means into the distributer circuit at the same time connecting the battery and interrupter in circuit with the second pair of contacts so that current impulses from the starting means are timed later than the service sparking current.
9. In an ignition system for explosive engines, spark producing coils having primary and secondary windings, a single circuit controlling lever having a contact at either end, one of said contacts being in the primary circuit of one coil and the other in the primary circuit of the other coil, and means for operating said controlling lever to first open the primary of one coil and then close the primary of the other coil, a distributer and a switch for switching the secondary of the

last mentioned coil into the distributer while disabling the action of the first.

10. In an ignition system for explosive engines, a service magneto having a circuit controller for timing the sparking current from said magneto, a wearing element carried by the controller, a cam for engaging the wearing element to actuate said controller, a contact member carrying a contact fastened to the end of the controller adjacent the wearing piece, a stationary contact to cooperate with the last mentioned contact, an induction coil having primary and secondary windings, a battery, a distributer and switch for connecting the primary of the induction coil, battery and said contacts into circuit at the same time connecting the secondary winding of the induction coil through the distributer and disabling the service magneto.

11. In an ignition system, the combination of a service ignition device having primary and secondary circuits, a main circuit breaker controlling one pair of contacts included in the primary circuit, a distributer, an auxiliary ignition device having primary and secondary circuits, a source of current, a second pair of contacts brought into closed position by the main circuit breaker after the first pair has been moved to open position, and a switch for including the source of current in circuit with the primary of the auxiliary ignition device and the second pair of contacts and also connecting the secondary of the auxiliary ignition device into the distributer, the said switch also serving at the same time to close a circuit for disabling the service ignition device.

In witness whereof I affix my signature.
LEO J. WERNER.
